(57) **CLAIM**

The ornamental design for a pair of seating recesses for a cleaning head, as shown and described.

DESCRIPTION

FIG. 1 is a bottom, front and left side perspective view of a pair of seating recesses for a cleaning head showing our new design;

FIG. 2 is a bottom plan view thereof;

FIG. 3 is a front elevational view thereof;

FIG. 4 is a rear elevational view thereof;

FIG. 5 is a left side elevational view thereof; and,

FIG. 6 is a right side elevational view thereof.

The claimed design is shown in solid lines in FIGS. 1 and 2. The details shown in broken lines are for illustrative purposes only and form no part of the claimed design.
